(57) **CLAIM**

We claim the ornamental design for a root vegetable product, as shown and described.

DESCRIPTION

FIG. 1 is a front perspective view of a first embodiment of the root vegetable product in accordance with our new design.

FIG. 2 is a left side view thereof;

FIG. 3 is front view thereof;

FIG. 4 is right side view thereof;

FIG. 5 is a rear view thereof;

FIG. 6 is a top plan view thereof;

FIG. 7 is a bottom view thereof;

FIG. 8 is a front perspective view of a second embodiment of our new design;

FIG. 9 is a left side view thereof;

FIG. 10 is a front side view thereof;

FIG. 11 is a right side view thereof;

FIG. 12 is a rear view thereof;

FIG. 13 is a top plan view thereof; and,

FIG. 14 is a bottom plan view thereof.
